CLAIM

The ornamental design for an artificial fishing lure, as shown and described.

DESCRIPTION

FIG. 1 is a side elevation of the artificial fishing lure of the present invention;

FIG. 2 is a view similar to FIG. 1 showing the oppositely extending portions of the lure in outwardly inclining disposition as when the lure is descending in water; and

FIG. 3 is a top view of the lure of FIG. 1.

The side of the lure not shown is identical to the side shown, and the bottom of the lure is identical to the top except for the absence of the hook.
